ROD MILL

Orpha G. Richardson, Fresno, Calif.

Application January 19, 1954, Serial No. 404,905

1 Claim. (Cl. 241—179)

This invention relates to rod mills and more particularly to a rod mill having drum carried rods or rollers and free rods or other impact elements, cooperating with the drum carried rollers to provide a grinding action.

It is among the objects of the invention to provide an improved rod mill having a drum supported for rotation about a substantially horizontal axis and having an inlet structure at one end and an overflow outlet structure at the other end of the drum; in which the drum includes a cylinder, head plates and end plates disposed at the respectively opposite ends of the cylinder, stay rods disposed against the outer surface of the cylinder at angular intervals therearound holding the head plates and end plates in position at the respectively opposite ends of the cylinder, and rollers disposed around the inner surface of the cylinder and journaled at their ends on the head plates; in which material pulverized by the mill is discharged through the end plates at both ends of the drum; in which either rods, balls or pebbles may be used in the drum as the material crushing elements; in which the end plates or grizzly plates are provided with apertures determining the particle size of the material discharged from the mill; which includes a sufficient number of separable parts to render the several parts light in weight and of small size compared to the parts of similar mills of corresponding capacity now in use so that the parts of the mill can be conveniently transported to mining locations that are remote and of difficult access; which includes parts that can be easily assembled together by a single mechanic in a short time to provide the complete mill; and which is simple and durable in construction, economical to manufacture, and efficient and effective in operation.

Other objects and advantages will become apparent from a consideration of the following description and the appended claim in conjunction with the accompanying drawings wherein:

Figure 1 is an end elevational view of the mill at the overflow outlet end of the mill;

Figure 2 is a fragmentary end elevational view of the inlet end of the mill;

Figure 3 is a longitudinal cross sectional view on the line 3—3 of Figure 1; and

Figure 4 is a transverse cross sectional view on the line 4—4 of Figure 3.

With continued reference to the drawings, the mill comprises a drum, generally indicated at 10, cylindrical sleeves 11 and 12 projecting one from each end of the drum 10 coaxially of the drum and providing bearing arbors outwardly of the corresponding ends of the drum, journal bearings 13 and 14 receiving the sleeves 11 and 12 respectively outwardly of the corresponding ends of the drum and rotatably supporting the sleeves for rotation of the sleeves and the drum about a substantially horizontal axis coincident with the longitudinal center line of the drum and sleeves, suitable pedestals or supports 15 and 16 respectively supporting the bearings 13 and

2

14, driving means, generally indicated at 17, for rotating the drum, and a feed scoop 18 mounted on the distal end of the inlet sleeve 11.

The drum 10 comprises a steel cylinder or barrel 20 of suitable size and wall thickness, a mill capable of pulverizing approximately one ton of ore in an hour having a cylinder of approximately 30 inches diameter, 40 inches length and a wall thickness of approximately one-quarter inch. Grizzly plates 21 and 22, in the form of steel disks of circular shape are disposed one against each end of the drum in closing relationship to the corresponding ends of the drum. These plates have centrally disposed, circular openings 23 and 24 and have a diameter somewhat greater than the external diameter of the drum 20 so that the marginal portion thereof projects outwardly beyond the outer surface of the drum. The plates 21 and 22 are provided, each with a circular series of angularly spaced apart apertures extending around the outer surface of the drum 20 and stay rods 25 extend longitudinally of the drum in contact with the outer surface of the drum and at substantially equal angular intervals around the drum and extend through corresponding apertures in the plates 21 and 22. The end portions of the stay rods 25 are screw threaded and nuts, as indicated at 26 and 27 are threaded onto the respectively opposite end portions of the stay rods and bear against the outer side of the plates 21 and 22 respectively to hold these plates firmly against the corresponding ends of the cylinder 20 and in fluid sealing engagement with the ends 30 of the cylinder.

Header plates 28 and 29 are disposed one at each end of the cylinder 20 in spaced and substantially parallel relationship to the corresponding grizzly plates 21 and 22. The header plates 28 and 29 are each provided with a circular series of apertures receiving the corresponding ends of the stay rods 25 and nuts, as indicated at 30 and 31, are threaded onto the stay rods at the outer side of the header plates 28 and 29 respectively to force these header plates against the outer ends of the corresponding nuts 26 and 27 which serve as spacers to maintain the header plates spaced from the outer surfaces of the corresponding grizzly plates. The header plates 28 and 29 are provided with centrally disposed openings 33 and 34 respectively and domed heads 35 and 36 are secured at 40 their open ends to the outer sides of the header plates 28 and 29 respectively coaxially of these plates. The domed heads 35 and 36 are hollow steel bodies of hemispherical or hemispheroidal shape and are provided with centrally disposed openings 37 and 38.

The inlet sleeve 11 extends through the central openings in the domed head 35, the header plate 28 and the grizzly plate 21 and is rigidly secured to the head 35 and header plate 28 by being welded thereto but is left free of the grizzly plate 21 so that the grizzly plate can be changed, when desired. It will be evident that the domed heads 35 and 36 braces the respective header plates 28 and 29 and forms a support therefor.

The outlet overflow sleeve 12, which is of larger diameter than the inlet sleeve 11, extends through the central apertures in the head 36, the header plate 29 and the grizzly plate 22 and is rigidly secured to the head 36 and header plate 29.

Cylindrically shaped rollers 40, of specially hard metal alloy are disposed within the cylinder 20 and extend longitudinally of the cylinder at substantially equal angular intervals around the inner surface of the cylinder. The grizzly plates 21 and 22 are provided respectively with circular series of angularly spaced apart holes with in the corresponding ends of the cylinder 20 and arbor pins, as indicated at 41, are journaled one in each aperture in the inner series of holes in the grizzly plate 21 and are inserted in coaxially disposed recesses in the

adjacent ends of the rollers 40. Arbor pins 42 are journaled one in each of the holes of the inner series of holes in the grizzly plate 22 and each of these pins 42 is received at one end in a coaxially disposed recess in a corresponding roller 40. The arbor pins 41 and 42 rotatably mount the rollers 40 on the grizzly plates 21 and 22 in position such that the rollers are slightly spaced from the inner surface of the cylinder 20 and are free to rotate about their own longitudinal center lines as axes. A spacing between the inner surface of the cylinder and the adjacent surface portions of the rollers of approximately one-eighth of an inch has been found to provide entirely satisfactory results in use.

Each grizzly plate is provided with a circular series of patches of small perforations within the corresponding end of the cylinder 20, each patch of perforations being disposed between two adjacent holes of the circular series of holes or apertures receiving the corresponding arbor pins 41 and 42 and the apertures being of a selected size to determine the particle size of the material discharged from the mill. Each aperture of the series 43 in the grizzly plate 21 and of the corresponding series in the grizzly plate 22 tapers somewhat from the outer to the inner surface of the corresponding grizzly plate so that pulverized particles of ore passing through these apertures will not tend to stick or jam in the apertures but will be washed freely through the apertures by the water intrained with the crude or unpulverized ore fed to the mill. The pulverized material discharged through the perforations in the grizzly plates at the respectively opposite ends of the drum cylinder 20 is discharged through the space between the grizzly plates and the adjacent end or header plates 28 and 29 and falls into a suitable receptacle 44 disposed below the drum of the mill.

Material crushing elements, as indicated at 46, 47 and 48 are freely disposed in the space within the cylinder 20 surrounded by the rollers 40, these elements being illustrated as heavy rods although other elements, such as tubes or balls can be used with advantage under different operating conditions of the mill. When the drum 10 is rotated the elements 46, 47 and 48 are carried upwardly on the rollers 40, centrifugal force causing these elements to stick to the inner side of the drum structure until the elements are raised to a position in the upper half of the space within the drum, whereupon the gravity of the elements overcomes the centrifugal force acting thereon and the elements fall to the bottom of the drum crushing material in the drum on the rollers 40. Because of their free rotation in the drum the rollers will be equally worn on all sides and will not be subjected to excessive wear which will necessitate their replacement at frequent intervals during the use of the mill. Also, because of this freely rotatable mounting of the rollers the rollers will roll under the material crushing elements and the material will be crushed into substantially precise particles without the production of slime or sludge such as is produced by sliding action of the crushing elements on the rods usually provided in such mills and fixed relative to the drum. The spacing between the rollers and the inner surface of the drum provides for the washing of the ore material in the drum freely from the inner surface of the drum so that all of the ore fed to the drum is rapidly crushed to desired particle size and discharged from the drum through the perforated grizzly plates at the ends of the drum. The drum will not become overloaded regardless of any excess of the intake rate over the discharge rate of the pulverized material since any excess material in the drum will be discharged through the overflow discharge sleeve 12 and, if desired, this overflow material can be returned by suitable means to the inlet end of the drum to be fed back into the drum.

An annular spur gear 50 is disposed in surrounding relationship to the domed head 36 of the drum and is rigidly secured to the head 36 coaxially of the drum so

that the domed head 36 defines a mounting for gear 50. Suitable bearing pillows 51 and 52 are mounted on the top of the pedestal 16 in spaced apart relationship to each other longitudinally of the axis of the drum and a drive shaft 53 is journaled in these bearings. A spur gear 55, smaller than the gear 50, is mounted on one end of the drive shaft 53 and meshes with the gear 50 and a suitable power plant is connected to the shaft 53 to rotate the spur gear 55 and turn the gear 50 and the drum 10 at a speed less than the rotational speed of the shaft 53.

A right angular scoop or dipper 57 is mounted on the distal end of the inlet sleeve 11 at the outer end of the bearing 13 and projects radially from the sleeve and also tangentially of the sleeve to dip or scoop up a mixture of material to be crushed and water from a suitable tank or hopper into which the dipper dips as the drum is rotated. A spiral rib or vane 58 extends through the interior of the feed sleeve 11 and around the inner surface of the feed sleeve to insure a uniform feed of the mixture of water and ore or other material to be pulverized, into the drum of the mill.

The particle size of the crushed material discharged from the mill can be varied by using different grizzly plates having correspondingly different size perforations therein, the rate of discharge can be controlled by the number of perforations in the grizzly plates and, if desired, one perforated grizzly plate can be replaced by a grizzly plate without the perforations 43 so that the discharge will take place at one end of the drum. Alternatively, both of the grizzly plates can be omitted and the corresponding header plates secured directly against the adjacent end of the drum to provide a center discharge mill discharging at one end only through the outlet overflow sleeve 12. In this case the rollers 40 would also be omitted and the material crushed directly against the inner surface of the wall of the drum.

The invention may be embodied in other specific forms without departing from the spirit or essential characteristics thereof. The present embodiment is, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

A rod mill comprising a drum mounted for rotation about its axis and having an inlet sleeve and an outlet overflow sleeve extending coaxially therefrom at respective opposite ends thereof, power driving means operatively connected to said drum adjacent one end thereof for imparting rotation thereto, material crushing means disposed within said drum for movement therewithin, said drum comprising a barrel, perforated grizzly plates disposed one against each end of said barrel in closing relation thereto, header plates disposed one at each end of said drum, means securing said grizzly plates and said header plates to said barrel with said header plates spaced from the outer sides of the adjacent grizzly plates to provide discharge spaces for pulverized material flowing from the interior of said barrel through said perforated grizzly plates, and dome-shaped heads secured at their open ends to each of said header plates and having centrally disposed openings therein respectively receiving said sleeves to reinforce the connections between said sleeves and drum and to provide braces for the respective header plates, one of said dome-shaped heads defining a gear mounting, said power driving means including a gear mounted on said one dome-shaped head.
